UNITED STATES PATENT OFFICE.

THOMAS E. HOWORTH, OF NASHUA, NEW HAMPSHIRE.

PROCESS AND MACHINE FOR PREPARING FIBER FOR DYEING.

1,322,695.

Specification of Letters Patent. Patented Nov. 25, 1919.

Application filed July 19, 1918. Serial No. 245,751.

To all whom it may concern:

Be it known that I, THOMAS E. HOWORTH, a citizen of the United States, residing at Nashua, in the county of Hillsborough and 5 State of New Hampshire, have invented certain new and useful Improvements in Processes and Machines for Preparing Fiber for Dyeing, of which the following is a specification.

10 This invention relates to processes and machines for preparing textile fibers for dyeing in mass.

Where fibers, such as cotton and wool, are to be dyed before the fiber is spun into yarn, 15 much better results are obtained if the fiber is first carded. Carded fiber is cleaner, it is spread out more evenly, and there are fewer bunches. Where uncarded fiber is dyed, it takes the dye unevenly, and where 20 it is afterward put through machines, such as pickers and cards, the dye has made the fiber brittle and there is more waste, noils, etc.

As now handled, carded fiber for dyeing 25 leaves the card in the form of sliver and is delivered into cans or boxes. These cans or boxes are removed to a picker, through which the sliver is passed for the purpose of beating it out and breaking it up so that 30 it will better take the dye. After passing through the picker, the broken up sliver is carried to the dye house.

The action of the beaters in the picker breaks the staple and thus injures it.

35 With my process and with my device attached to each card, the sliver is drawn apart and separated without breaking the staple and can be dropped directly onto a conveyer apron or into a pneumatic carrier which delivers it directly to the dye room.

With my attachment on his cards, a carder 40 can operate many more cards than without it because there is no necessity for piecing 45 broken ends of sliver.

The services of the man or men who carry the boxes filled with sliver to the picker, the services of the man or men on the pickers, and the services of the man or 50 men who carry material from the picker to the dye house are dispensed with.

My process and machine can be used in connection with a single card, but is more useful where a number of cards are operating together, preferably in line.

In the drawings, Figure 1 is a plan view of the delivery end of a card with my device attached. Fig. 2 is an elevation from the front of my attachment, on a somewhat larger scale than Fig. 1. Fig. 3 is an elevation from the left of Fig. 2, the gears being broken away and outlined. Fig. 4 is a section from the left on line 4-4 of Fig. 2. Fig. 5 is a diagram, shown in elevation from the front, of a plurality of cards which deliver into a common conveyer. Fig. 6 is an elevation from the left, similar to Fig. 3, of a modification of the drive mechanism with a different location of the rolls. Fig. 7 is a side elevation showing a pair of fluted 65 separating rolls instead of plain rolls.

A represents the frame of a cotton card of any well known type. B represents the main cylinder, C, the doffer, D the doffer comb, F the trumpet guide, and G the sliver. 70 The card shown is supposed to be of the revolving flat card type and has the usual smooth calender delivery rolls H and K carried by shafts 11 and 14, which are supported by any suitable parts of the frame, such as boxes or brackets 15 and 16, all in a well known manner. Roll K is driven from the train of gears 10 by shaft 11 and positively drives roll H through the medium of gears 12 and 13, carried respectively by shaft 11 75 and counter-shaft 14 which carries gear 13 and roll H. The parts described in this paragraph are all old.

Preferably, to supports 15 and 16, I attach the brackets 20 and 21 as by screws 17. 80 These brackets, as shown in Figs. 1 to 5, extend upward and outward at an angle of about forty-five degrees. Each bracket has a longitudinal slot, such as shown at 22 in Fig. 4, and at the lower end of this slot 95 rests a bearing 24 for a counter-shaft 25 which carries what I will call my lower separating roll O.

Slidable in channel 22 is also a bearing 30 for another counter-shaft 31 which carries 100 the upper separating roll P. I may use a stud 32 on bearing 30 and a stud 33 on a top plate 34, with a spring 35 between them to permit the upper separating roll P to give in case a bunch passes through. Separating rolls O and P are driven by a suitable chain of gears from shaft 11. As shown, gear 40 is carried by shaft 11 and engages a pinion 41 revoluble with shaft 42 which carries gear 43, as shown in Fig. 3.

Gear 43 engages pinion 44 carried by shaft 25 which carries lower separating roll O, and also gear 45 which engages a gear 46 carried by shaft 31, which also carries separating roll P.

As a result of this arrangement, separating rolls O and P are positively driven at a certain surface speed relative to the surface speed of delivery rolls H and K dependent 10 upon the arrangement of the train of gears and the size of the gears.

As shown, this gives a relative speed which determines the draft on the sliver G which passes through the delivery rolls H 15 and K and through the separating rolls O and P of about 7.6.

It is very desirable, if not necessary, that lower delivery roll K and separating roll O should come very close together, and I find 20 it convenient to make separating rolls O and P relatively large and smooth, as the purpose of my device is to create sufficient draft on the sliver so that it will be drawn out until it is drawn apart and separated into 25 flakes which are suitable for immediate use in dyeing.

With this arrangement of rolls, it is immaterial whether or not the ends break between the delivery rolls H—K and separating rolls O—P, as any broken piece will be picked up by the roll O and carried along through, being delivered at M in flakes.

In fact, by my process, the sliver is continuously drawn out and repeatedly separated, the sliver but not the fiber being broken. The sliver is drawn out longitudinally until it separates into flakes but the 35 staple is not broken.

The amount of draft and the amount of 40 difference between the surface speeds of the delivery and separating rolls will vary with different stock, but I find that a draft of 7 or more is desirable with ordinary medium staple cotton stock.

45 While my device and process are suitable for a single card, I find it especially useful where a plurality of cards, each having delivery rolls and separating rolls, are arranged, preferably, in line, as shown in Fig. 5. The cards 50, 51, 52, each have separating rolls O—P and each also has a spout or tube, such as 54, into which the stock, after being separated into flakes, is delivered.

These spouts all deliver to a common conveyer which is shown in Fig. 5 as tube 55 which runs underneath the floor 56. A suction blower 57 creates an air current which delivers the flaky stock into the dye room or any other suitable delivery point 58.

60 This conveyer may be pneumatic, as shown, an endless apron, or any other similar device of well known character.

While I prefer to arrange my separating rolls at an angle of forty-five degrees, I may, 65 as shown in Fig. 6, arrange the separating

rolls R and S in front of, below, and at right angles to the delivery rolls, such as H and K, and I may drive them by means of suitable sprockets 60, 65, 66, 61 connected by chains 62, 67. I show roll S as positively 70 driven at the same speed with roll R by means of gears 63 and 64.

With this arrangement of rolls, broken ends cause no difficulty, because the rolls R and S are continuously turning in the direction of the arrows and actually pick up the ends as fast as they are pulled apart, such pulling apart being the purpose of the machine.

The rolls R—S are shown as smaller than 80 O—P, and my device will work properly with such smaller smooth rolls. As shown in Fig. 7, in place of smooth rolls I may use fluted rolls, such as T—V, if desired, but I find that less power is required with smooth 85 rolls and therefore prefer them.

Similar fluted rolls I show in application for patent on drawing attachment for cards pending herewith, and I may use my process on the machine there shown. The principal 90 feature of my process, as described herein, is the continuous drawing out of a carded and condensed sliver until it separates into flakes.

This may be accomplished by the mechanism shown or by any other mechanism which will put sufficient draft on the sliver and which will pick up the continuously formed broken ends as fast as they are formed.

I prefer to arrange the axes of the separating rolls in a plane which is at an angle of forty-five degrees with a plane through the axes of the delivery rolls, but this angle may be more or less. I prefer to arrange 105 the separating rolls in front of, that is on a line running from the front to the back of the card and either about on a level with or below the delivery rolls but other arrangement of parts might be made.

The drive mechanism for the separating rolls is preferably capable of adjustment as by changing gears or chains and sprockets, and should be adjusted so that these rolls will revolve at so much greater speed than the delivery rolls that the sliver will be drawn out longitudinally until it separates into flakes.

I claim:

1. The process of preparing fiber for dyeing which consists of passing it through a carding machine, condensing it into a sliver, and of drawing out the sliver without breaking the staple until it separates.

2. The process of preparing fiber for dyeing which consists of breaking up a homogeneous sliver into separate elements by drawing it apart longitudinally.

3. The process of preparing fiber for dyeing which consists of continuously carding,

condensing and drawing it apart longitudinally until it is repeatedly separated into flakes.

4. The process of treating sliver which 5 consists of drawing it out continuously to such a point that it separates into flakes.

5. The combination of a card having sliver delivery rolls, with smooth relatively large separating rolls located in front of the delivery rolls, the lower delivery and separating rolls being close together, and the upper delivery and separating rolls being relatively farther apart, and mechanism positively revolving the separating rolls at a greater 10 surface speed than the delivery rolls.

6. The combination of a card having sliver delivery rolls, with separating rolls located in front of the delivery rolls, the lower delivery and separating rolls being close together, and the upper delivery and separating rolls being relatively farther apart, and mechanism for revolving the separating rolls at a greater speed than the delivery rolls.

7. The combination of a card having sliver delivery rolls, with separating rolls located in front of the delivery rolls, the lower de-

livery and separating rolls being close together, and mechanism for revolving the separating rolls at so much greater speed than the delivery rolls that the sliver is 30 drawn out and separated.

8. The combination of a plurality of cards each having delivery rolls and separating rolls so arranged with reference thereto and revoluble at such speed as to draw apart the 35 sliver, with a conveyer to which the separated stock from the cards is delivered.

9. The combination of a card having sliver delivery rolls, with separating rolls located in front of the delivery rolls, the lower delivery and separating rolls being close together, and mechanism for revolving the separating rolls at a greater speed than the delivery rolls.

10. The process of preparing fiber for dyeing which consists of continuously forming it into a sliver and of drawing the sliver apart longitudinally until it separates into flakes.

In testimony whereof I affix my signature. 45

THOMAS E. HOWORTH.
